(57) **CLAIM**

The ornamental design for an electric toothpick head, as shown and described.

DESCRIPTION

1. Electric toothpick head

1.1 : Right front perspective view

1.2 : Left rear perspective view

1.3 : Front elevation view

1.4 : Rear elevation view

1.5 : Top plan view

1.6 : Bottom plan view

1.7 : Right elevation view

1.8 : Left elevation view

1.9 : Enlarged partial view

1.10: Enlarged partial view

Fig. 1.9 is an enlarged view of portion 1.9 of fig. 1.1; fig. 1.10 is an enlarged view of portion 1.10 of fig. 1.2; in figs. 1.1 to 1.10, the broken lines of even length depict portions of the electric toothpick head that form no part of the claimed design, the dash-dot lines depict the boundary of the claimed design but form no part thereof, and the long dash-short dash-short dash lines depict boundaries but form no part of the claimed design.
